UNITED STATES PATENT OFFICE.

FREDERICK AUGUSTUS ARBENZ, OF PHILADELPHIA, PENNSYLVANIA.

TAKE-UP MECHANISM FOR LOOMS.

SPECIFICATION forming part of Letters Patent No. 388,615, dated August 28, 1888.

Application filed January 4, 1887. Serial No. 223,372. (No model.)

To all whom it may concern:

Be it known that I, FREDERICK AUGUSTUS ARBENZ, a citizen of Switzerland, residing in the city and county of Philadelphia, State of Pennsylvania, have invented a new and useful Improvement in Take - Up Mechanism for Looms, which improvement is fully set forth in the following specification and accompanying drawings, in which—

10 Figure 1 represents a side elevation of a portion of a loom having the take-up mechanism embodying my invention applied thereto. Fig. 2 represents a longitudinal vertical section in line $x-x$, Fig. 3. Fig. 3 represents a 15 transverse vertical section in line $y-y$, Fig. 1. Fig. 4 represents an end view of a modification. Fig. 5 represents a side elevation of the portion shown in Fig. 4. Fig. 6 represents a side view of a modification. Fig. 7 represents 20 a top view of another modification. Fig. 8 represents a side elevation of Fig. 7. Fig. 9 represents a vertical section of the portion in line $z-z$, Fig. 3.

Similar letters of reference indicate corresponding parts in the several figures.

25 My invention relates to improvements in take-up mechanisms for looms; and it consists in the combination and arrangement of parts, as hereinafter set forth and claimed, whereby the take-up operation is effectively accomplished, means being provided to prevent any undue strain owing to back action of the winding-drum.

Referring to the drawings, A represents the 30 frame of a loom, and B the lay thereof, both of usual construction.

C represents the reed located in a frame, the lower bar, C', of which is secured to arms D, the upper ends whereof are fitted to journals D', which are mounted in bosses D² rising from the lay. The upper cross-bar, D³, of the said frame is connected with said arms D by means of bolts E, which are secured to the ends of said bar and pass through slots E' in the arms D, whereby said cross-bar D³ may be vertically 45 adjusted. The bolts E carry nuts E'', which tighten against the arms D and serve to hold the bar D³ in adjusted position.

Attached to the ends of the bar C' are arms F, whose lower ends carry pins F', each of

which pins enters the bifurcated limb of a weighted elbow-lever, G, whose bearings are on the axes G' of the lay.

To one of the journals D' is secured a vertical arm, H, to whose lower end is secured a 55 rod, J, which extends forward from said arm and is freely fitted to an arm, K, the latter having hung to it a pawl, K', which engages with a ratchet, L, on the shaft of a wheel of a train of gearing, M, one of said wheels being connected with the shaft of the winding-drum N of the loom.

P represents a check-pawl, which is mounted on the frame A and engages with the ratchet L for preventing return motion of the ratchet. 60

Q represents a spring which encircles the rod J and is interposed between the arm K and a collar, R, the latter being mounted on said rod J and having a side opening in which a screw is fitted, so that the said collar is adjustably connected with said rod J, whereby the tension of the spring may be adjusted. The arm K has an opening through which the rod J freely passes, the said rod having a screw-threaded end for a nut, R'', so as to secure the 75 arm on the said rod.

It will be seen that the inner end of the journal D', to which the arm H is secured, is squared, so as to enter an angular opening in the connected arm D, whereby as said arm D 80 is moved it rotates said journal D', and consequently operates said arm H.

The operation is as follows: As the lay advances, the reed is stopped by contact with the fell of the cloth, and the lay still advancing, 85 the journals D' oscillate in their bearings, the lower part of the arm F, carrying the pin F', being thrown backward, so as to press against the rear fork of the bifurcated arm of the lever G, and thereby raise the weighted arm 90 thereof, the said weighted arm causing the rear fork to press against the pin when the lay is pushed backward at the completion of the forward motion, and thereby restoring the reed to its normal or vertical position. At the time 95 of the oscillation or partial rotary movement of the journal D' the arm H is moved so as to operate the arm J, and thereby the arm K, in such manner that the pawl K' on the upper part of said arm rides freely over the teeth of the 100

ratchet L. When the lay returns, the weighted lever G causes the arms F to assume their normal positions, the return movement of the said arms F causing the journal D' to so operate 5 the arms H and J, and thereby the arms K, that the pawl K' is caused to rotate the ratchet L, and consequently the train of gearing M, whereby the drum N is rotated and the fabric wound thereon. Should there be any strain 10 on the drum due to back action or resistance of the fabric, said strain being transmitted to the ratchet L, this occurring as the pawl advances, the lower end of the arm K slips on the rod J, whereby breakage of the pawl or 15 the arm, or both, is prevented. When the strain is relieved, the spring Q restores the arm K to its normal position.

In Figs. 1, 3, and 4 I show in dotted lines a rod, J', and spring Q', one end of the rod being pivoted to the upper extended end of the arm K. The other end of the rod passes freely through the lay and carries a collar, R', between which and the lay the spring Q' is located. In this case the spring Q on the rod 25 J is omitted, and the arm K is pivotally secured to the rod J; but the result is the same as that hereinbefore stated, the operation being, however, slightly different, in that in the event of strain on the drum N as the pawl K' 30 advances the rod J' causes the spring Q' to yield, and thus relieve the pawl, and consequently the arm K and connected parts.

In Figs. 4 and 5 the arm H is shortened and does not extend to the journal D', but is 35 extended laterally, joining one of the arms F, the locations of the elbow-lever G and pins F' being somewhat raised from the position shown in Figs. 1, 2, and 3, without, however, producing different results.

40 In Fig. 6 the arm H has its lower end forked to engage with a pin, F², on lever F³, which is pivoted to the frame of the loom, said lever F³ having secured to its upper end an eye, Q², through which freely passes the rod J', the latter having the collars Q³ and Q⁴ thereon. A 45 spring, Q', is interposed between the eye Q² and the collar Q³ on the end of the rod J'. As the lay advances and the journal D' is rocked by the movement of the arm D, the arm H is 50 moved so that its lower forked end operates on the pin F² of the lever F³, moving the lower end of said lever F³ to the right. This moves the upper end of the lever F³ to the left, and thus operates the rod J', whereby the pawl 55 rides freely over the ratchet. On the return motion the pawl rotates the ratchet, and in the event of strain on the latter the spring Q' yields and prevents breakage of the parts.

In Figs. 7 and 8 one of the wheels M is a 60 worm-wheel, and meshes with a worm, M', which is fixed to a shaft, M², on which is loosely fitted a collar, M³, to which is hung one or more pawls, K', which engage with a ratchet, L, to which the shaft M² is firmly secured. A rod, J, is connected with said collar M³ and operated similarly to the rod shown

in Figs. 1, 2, and 6, and carries a spring for relief of the parts in the event of strain on the drum N.

The top of the arm H carries a weight, H', 70 to assist in restoring said arm to its normal position.

Having thus described my invention, what I claim as new, and desire to secure by Letters Patent, is—

75 1. A lay with bosses, and journals having bearings in said bosses, in combination with a frame carrying a reed, and slotted arms connecting said frame and journals, arms connected at their upper ends to said frames and provided at their lower ends with pins, weighted levers each having a bifurcated end in which said pin works, a vertical arm secured to one of said journals, so as to oscillate therewith, a winding-drum with pinion on its journal, and 80 mechanism, substantially as described, connected to said pinion and vertical arm, for converting the oscillating motion of the arm into the rotary movement of the drum, substantially as described.

90 2. A lay, in combination with the journals D', having bearings in bosses connected to said lay, a frame secured to said journals, a reed in said frame, the arms F, secured to said frame and provided with the pins F' at their lower 95 ends, the weighted levers G, each having a bifurcated end, the vertical arm H, secured to one of said journals D', so as to oscillate therewith, a winding-drum having a pinion on its journal, a train of gearing with ratchet-wheel, 100 a pivoted lever with a pawl, and a rod connected to said arm H and adapted to oscillate the said pivoted lever, substantially as and for the purpose set forth.

105 3. A lay with bosses and a frame having a reed therein, in combination with journals having bearings in said bosses, the vertical arm H, secured to one of said journals, the rod J, the arm K, having the pawl K', a winding-drum with pinion thereon, and a train of gearing between said arm K and pinion of winding-drum, the said train having a ratchet adapted to be operated by said pawl K', so as to rotate said winding-drum, substantially as 110 described.

115 4. A lay with bosses, and journals having bearings in said bosses, in combination with a frame carrying a reed, and arms connecting said frame to said journals, the vertical arm H, secured to one of said journals, the rod J, 120 connected to the arm H and having the collar R thereon, the arm K, loosely fitted on the rod J, the spring Q, located on said rod J between the collar R and arm K, the nut R'', the pawl K' on arm K, a train of gearing having 125 the ratchet L, adapted to be operated by said pawl K', and a winding-drum having a pinion operated by said train of gearing, substantially as described.

130 5. A lay with bosses D² and journals D', in combination with the vertical arm H, the arm K, with pawl K', an operating-rod con-

necting said arms H and K and having a collar with clamping-screw thereon, a winding-drum having a pinion, a train of gearing with a ratchet adapted to operate said drum, and a spring between said arm K and said collar on operating-rod, normally adapted to bear against said arm K, but adapted to yield in

case of unusual resistance of the ratchet-wheel, due to strain on the winding-drum.
